DESIGN FOR A FINGER RING

Albert Nalick, Los Angeles, Calif.

Application August 26, 1946, Serial No. 132,869

Term of patent 3½ years

(Cl. D45—10)

To all whom it may concern:

Be it known that I, Albert Nalick, a citizen of the United States, residing at Los Angeles, in the county of Los Angeles and State of California, have invented a new, original, and ornamental Design for Finger Ring, of which the following is a specification, reference being had to the accompanying drawing, forming part thereof.

Fig. 1 is a top plan view of a finger ring showing my new design.

Fig. 2 is a front elevational view thereof.

Fig. 3 is a side elevational view.

I claim:

The ornamental design for a finger ring, substantially as shown.

ALBERT NALICK.
